DALLAS B. HATHAWAY, OF NEW BEDFORD, MASSACHUSETTS, ASSIGNOR TO THE WHITIN MACHINE WORKS, OF WHITINSVILLE, MASSACHUSETTS, A CORPORATION OF MASSACHUSETTS.

STOP-MOTION.

1,117,489.

Specification of Letters Patent. Patented Nov. 17, 1914.

Application filed October 22, 1912. Serial No. 727,096.

To all whom it may concern:

Be it known that I, DALLAS B. HATHAWAY, of New Bedford, in the county of Bristol and State of Massachusetts, have invented the new and useful Improvements in Stop-Motions hereinafter fully set forth.

The invention is an improvement in sliver pan stop motions and consists in a simple construction of sliver pans adapted for use 10 with the stop motion apparatus of Heilman type combing machines in an effective and reliable manner, as will be hereinafter fully described and more particularly pointed out in the claims.

15 The object of the invention is to eliminate the objections to the sliver pans now generally in use which arise from the fact that they require to be loosely mounted or supported so as to be capable of moving forwardly under the pull of a bunched sliver to stop the motion of the machine. The instability of such sliver pans, consequent to such movability of their mounting, results in their frequently becoming stuck in their 20 normal position and failing to slide into electrical circuit-making or circuit-breaking position to actuate the stop motion apparatus. My present invention provides for the elimination of this and other difficulties 25 attendant upon the existing forms of construction, and also provides certain improvements in the manufacture of the pan which will be apparent to those skilled in this art.

30 In the accompanying drawings, forming part hereof, Figure 1 is a vertical section of a sliver pan in position in a Heilman comb, and includes a diagram of the stop motion apparatus; Fig. 2 is a similar view 35 of substantially the same parts with the trumpet device in position to stop the machine.

As shown in the drawings, the sliver pan is mounted between the detaching rolls 1 and the calender rolls 2 and 3, the function 40 of this pan being as usual to conduct the pieced fleece emerging from the piecing rolls to the calender rolls, at the same time folding and condensing such fleece into a 45 round sliver, which is delivered by the calender rolls upon the sliver apron 4 and thence passes to the delivery portion of the machine. The lower calender roll is carried 50 on the usual shaft journaled in the frame uprights 5 of the comb, while the upper

calender roll is supported by a bracket 6 secured to the under side of the sliver apron by suitable means, not shown, and electrically insulated from it. During the normal operation of the machine the sliver passing 60 between the calender rolls keeps them separated but when such sliver for any reason fails and the rolls come into contact with each other, the electrical communication thereby established between them closes a 65 stop motion circuit, such as indicated in Fig. 1, and stops the machine. This circuit includes a source of electrical energy and an electro-mechanical apparatus represented by 70 7, for stopping the belt or turning off the power, one terminal of the circuit being grounded or connected to the frame of the machine, as shown at 8, and the other to the insulated bracket, as shown at 9. The sliver pan stop motion of this invention may 75 utilize this same circuit or any other similar circuit or means for arresting the machine's motion.

The sliver pan comprises a pan body and a trumpet device. The pan body, marked 80 10, is formed of a perforated floor portion 11, side walls 12 and a front wall 13. At its rear end it is substantially the width of the fleece that emerges from the detaching rolls and at its forward end it may be of no 85 greater width than is necessary to receive and support the trumpet device, though the shape of the pan is immaterial to this invention. Such a pan can be stamped or pressed out of a flat sheet metal blank with 90 the desired perforations in the floor and end wall, and as shown herein is so made. The rear margin of the perforated floor portion 11 is turned downwardly forming a lip or hook 14 which is adapted to be seated in a 95 clip 15, the latter being mounted on the casting wall 16 or upon any other suitable fixed support, and adapted to engage the lip 14 in such wise as to prevent movement of the pan toward or from the calender rolls but 100 allow the pan to be lifted vertically out of engagement with the clip in an obvious manner. The forward end of the pan rests on the end of a set screw 17 carried on a longitudinal bar 18, the latter being supported as usual on the upright frame portions 5. As shown in the drawings the end 105 of this set screw may be received in a socket 19, secured to the under side of the pan body if desired but such attached socket is 110

not necessary if the seat for the rear portion of the pan is rigidly supported as above described in a substantially fixed position. Adjustment of the set screw allows the forward end of the pan to be raised or lowered as may be necessary for adjusting its position with reference to the calender rolls.

The trumpet device of the pan is secured in the aperture punched in its front wall 13 and includes a trumpet proper 20, which is movable under the pull of the bunched sliver and against the pressure of a spring so as to be thereby brought into contact with the terminal members 2 and close the circuit above referred to. In its preferred form the trumpet device includes the support for the movable trumpet, which is formed by an outer shell portion 21 and an inner tube section 22, the one being 20 screwed into the other and clamping the margin of the aperture between them so as to be thereby held in position concentric with the aperture. The entrance to the tube section 22 is desirably flared as indicated, 25 so as to coöperate thereby with the internal taper of the moving trumpet 20 in folding and condensing the flat fleece into rounded form. The moving trumpet is mounted within and concentrically to the flaring tube 30 section 22 and is provided with a cylindrical barrel portion adapted to slide in the forward orifice of the shell member 21 and also with a helical spring 23 which is confined between the shell member and a head or 35 shoulder on the rear end of the moving trumpet. The said spring is thus arranged to press the trumpet in a rearward direction, counter to the normal frictional pull of the sliver thereon, and a nut 24 screwed 40 to the forward end of the moving trumpet limits its motion in this direction and thus determines the normal position of the trumpet when the machine is running. It will be observed that the helical spring is 45 concentric to the axis of the trumpet and that the construction conceals and protects it against the entrance of dirt to the chamber in which it is confined. It will also be observed that the nut 24 is exterior to the 50 passage through the trumpet device and that lint or dirt is thus least likely to become interposed between it and its abutment surface, for which reason the disposition of the abutments as shown in the drawings is preferred. By this means the head 55 of the moving trumpet can slide directly on the surface which forms the entrance to the part 22 and thereby eliminate any obstruction, from the interior, to the free movement of the moving member. According to 60 the length of the moving trumpet and the adjustment of the set screw 17, the nut 24 or the end of the trumpet itself may be adapted to have contact with the upper calender roll 2 or with some other part where-

by the stop motion system will be put in operation whenever the abnormal pull of the sliver draws the trumpet forwardly against the pressure of the spring as shown by Fig. 2. Such contact will close the circuit indicated in Fig. 1 and by actuating the mechanism 7 will stop the machine as will be readily understood. The detail of the mechanism 7 forms no part of this invention, and being well understood is not illustrated or described, but it will be apparent that it may operate either on the making or breaking of the stop motion circuit as desired. Such a mechanism is shown, for example, in the co-pending application of 80 A. F. Waldow filed May 7th, 1913, Serial No. 765,983. It will be further evident that the tension of the spring may be adjusted or selected so as to permit movement of the trumpet on any desired increase of the sliver pull, less or greater than that necessary for pulling the whole sliver pan forwardly as heretofore.

The invention claimed is as follows:

1. In a sliver stop-motion mechanism, a 90 trumpet device comprising a tubular support, a trumpet sliding therein, a spring urging the trumpet counter to the sliver, and a contact member engaged by said trumpet when moved by the sliver. 95

2. In a sliver stop-motion mechanism, a trumpet device comprised of two relatively sliding members, both provided with a flaring passage for sliver, spring means urging one of the members counter to the sliver, 100 and a stop-motion element operated by said member.

3. In a sliver stop-motion mechanism, a trumpet device comprised of two telescopically related members, a spring inclosed 105 between said members and tending to resist the movement of one of them by the pull of the sliver, and a part adapted to be engaged by said member when moved against the spring. 110

4. A sliver stop-motion mechanism comprising a trumpet device having a support provided with an entrance for the sliver, a trumpet adapted to move within such support with its larger end sliding on the surface forming the said entrance, a spring urging said trumpet counter to the sliver, and means for limiting the spring-urged movement of said trumpet. 115

5. A sliver stop-motion mechanism comprising a trumpet device consisting of an outer shell serving as a support, a trumpet sliding within the shell, a spring within the shell urging the moving trumpet counter to the movement of the sliver therethrough, and means whereby the movement of the trumpet in the opposite direction is made effective to operate the rest of the stop motion mechanism. 125

6. A sliver stop-motion mechanism com-

prising a trumpet device including a support, a trumpet sliding therein, means urging the trumpet counter to the sliver and means for adjusting the normal position of 5 the trumpet with relation to the support.

7. A sliver stop motion mechanism comprising a trumpet device, including a support, a trumpet sliding therein, a spring urging the sliding trumpet counter to the 10 sliver, means for adjusting the normal position of the trumpet with relation to the support, and an electric circuit having a terminal engaged by said trumpet.

8. In a comber, a sliver pan for conducting 15 the sliver from the piecing to the calender rolls, comprising a pan body fixed against movement by the sliver, a trumpet mounted on the pan body to be moved forwardly thereon by the pull of the sliver, 20 and a stop-motion system having a contact member engaged by the forwardly pulled trumpet and operating thereby to stop the comber.

9. In a Heilman comber, a sliver pan 25 movably mounted between the piecing and calender rolls, means for supporting the body of said pan, holding it fixed against the pull of the sliver, a sliver trumpet supported by the pan body, free to move relatively 30 thereon by the pull of the sliver, a trumpet spring opposing such movement, and a stop-motion circuit having one of its terminals connected with said trumpet and the other with one of said calender rolls.

35 10. In a comber, a sliver pan having a trumpet subject to movement thereon by the pull of a bunched sliver, and a helical spring concentrically disposed with reference to the trumpet and acting thereon to resist such 40 movement, in combination with stop-motion mechanism controlled by the movement of the trumpet against the spring.

45 11. In a comber, a sliver pan having a pan body pressed from a single piece of sheet metal and a trumpet movably mounted

thereon, in combination with a spring holding 50 said trumpet against the pull of the sliver, and a stop motion mechanism engaged by the trumpet in its counter-spring movement.

12. In a comber, a sliver pan comprising a pan body fixed against movement by the sliver and a two part trumpet device providing a tapered sliver aperture for folding the fleece, one of such trumpet parts being 55 fixed to the body and the other being movable relatively thereto and controlling a stop motion system.

13. In a comber, a sliver pan body and a two part trumpet, one part of the trumpet 60 device being fixed to the body and the other being slidingly guided by the fixed part, in combination with a concentrically disposed helical spring between said parts and a stop motion system controlled by the movement 65 of the said part against its spring.

14. In a comber, a sliver pan body having an aperture in its front wall portion, and a trumpet support formed of two members adapted to clamp the wall between them, in 70 combination with a stop motion system and a spring-pressed moving trumpet member mounted to slide on the said support to control such stop motion system.

15. In a sliver stop-motion mechanism, 75 the combination of a trumpet mounted to move in a straight line coincident with the axis of the sliver passage therethrough, means urging the trumpet in a direction counter to the movement of the sliver, and 80 a member engaged by said trumpet when moved by the sliver.

In testimony whereof, I have signed this specification in the presence of two witnesses.

DALLAS B. HATHAWAY.
